ELECTRIC GUITAR

Junior R. Cole, Rte. 2, Box 62, Qulin, Mo., and
Archie L. Brown, Broseley, Mo.

Filed July 31, 1959, Ser. No. 57,020

Term of patent 14 years

(Cl. D56—1)

FIG. 1.

FIG. 2.

Figure 1 is a perspective view of an electric guitar, according to the present invention, showing our new design and as viewed from one side and the smaller end, and

Figure 2 is a perspective view viewed from the other side and larger end, after the guitar has been rotated 180 degrees from the position illustrated in Figure 1.

It is noted that the electric guitar of the illustrated design is a four-sided elongated box structure tapering from one end to the other end and rotatable about a horizontal pole, with all of the sides alike.

We claim:

The ornamental design for an electric guitar, as shown and described.
